UNITED STATES PATENT OFFICE.

MATTHIAS A. DIETRICK, OF PATTON, PENNSYLVANIA.

WINDOW SCREEN.

Application filed June 14, 1922. Serial No. 568,286.

To all whom it may concern:

Be it known that I, MATTHIAS A. DIETRICK, a citizen of the United States, residing at Patton, in the county of Cambria and State of Pennsylvania, have invented certain new and useful Improvements in Window Screens, of which the following is a specification, reference being had to the accompanying drawings.

- 10 This invention relates to certain improvements in window screens, and has relation more particularly to a device of this general character of a rolling type and it is an object of the invention to provide a novel and improved screen embodying a flexible fabric adapted to be disposed across a window opening together with a container or housing for said flexible element when the same is in inoperative position.
- 20 Another object of the invention is to provide a novel and improved device of this general character embodying a housing or casing in which the screen or kindred flexible fabric is adapted to be housed together with means associated with said container or housing for holding said container or housing in applied position with respect to a window casing or frame.

30 The invention consists in the details of construction and in the combination and arrangement of the several parts of my improved window screen whereby certain important advantages are attained and the device rendered simpler, less expensive and 35 otherwise more convenient and advantageous for use, as will be hereinafter more fully set forth.

The novel features of my invention will hereinafter be definitely claimed.

- 40 In order that my invention may be the better understood, I will now proceed to describe the same with reference to the accompanying drawings, wherein:—

Figure 1 is an elevational view illustrating 45 a screen constructed in accordance with an embodiment of my invention and in applied position;

Figure 2 is a sectional view taken substantially on the line 2—2 of Figure 1;

50 Figure 3 is an enlarged sectional view taken substantially on the line 3—3 of Figure 1;

Figure 4 is a view partly in section and 55 partly in top plan, illustrating the device as herein set forth;

Figure 5 is a sectional view taken substantially on the line 5—5 of Figure 1;

Figure 6 is a fragmentary elevational view illustrating a modified form of the invention;

Figure 7 is a fragmentary view in top 60 plan of the structure illustrated in Figure 6;

Figure 8 is a fragmentary view in elevation illustrating a further embodiment of my invention; and

Figure 9 is a view in perspective of a tool 65 for effecting the desired rotation of the rod comprised in the housing or receptacle.

As disclosed in the accompanying drawings, S denotes the sill of a window frame or casing and J the jambs associated therewith 70

1 denotes a plate held to the sill S adjacent a jamb J by a screw 2 or the like, said plate 1 being herein disclosed as substantially semi-circular in formation with its straight edge opposed to the jamb J and substantially 75 defined by an upstanding flange 3. Extending from an end portion of the straight edge of the plate 1 and disposed toward the jamb J is a finger 4 possessing a certain degree of inherent resiliency and which has its outer 80 or free end portion disposed on a predetermined upward curvature.

5 denotes a second plate having one end provided with an upstanding flange 6, said flange being pivotally connected through the 85 medium of the bolt 7 or the like with a jamb J and at a point preferably above the lower or meeting rail of the upper sash when said sash is in its closed position. This plate 5 overlies the portion of the sill S between the 90 associated jamb and the plate 1 adjacent thereto.

The side marginal portions of the plate 5 are provided with overlying flanges 8 which provide guide-ways for the sliding lock plate 95 9. This lock plate 9 is provided with a button hole slot 10, the larger end of which registers with an opening 11 in the plate 6 upon outward movement of the plate 9. The restricted portion of the button hole slot 10 100 is of a width less than the diameter of the opening 11 for a purpose to be hereinafter more particularly referred to. The outer end portion of the plate 9 is defined with an upstanding flange 12 to facilitate the manipulation of such plate.

H denotes a housing or container which is adapted to fit substantially snug between the sill S and the upper plate 5. This housing or container H is substantially 110

rectangular in cross section and the body portion 15 of this housing is formed of a single sheet of material bent into requisite form, with the longitudinal edges of said strip, in the completed device, separated to provide an entrance slot 16. These longitudinal edges are also defined by the returned flanges 17. Coacting with the opposite ends of the body 15 of the housing or receptacle H are the caps 18, said caps snugly fitting within the end portions of the housing or receptacle H and to facilitate such engagement of the caps, each of the caps is defined by the marginal flanges 19, certain of said flanges interlocking with the flanges 17 whereby the body 15 of the housing or receptacle H is maintained in fixed formation.

The caps 18 at the axial centers thereof are provided with openings 20. Disposed lengthwise through the housing or receptacle H is a rod R herein disclosed as angular in cross section and having one end portion upset or otherwise enlarged as at 25 21, said enlargement seating within a pocket 22 formed in the bottom cap 18 so that when the housing or receptacle H is in applied or working position the rod R will offer no hindrance or obstruction. The rod 30 R is disposed through the openings 20 in the caps 18 and through the opening 11 in the plate 6 and through the button hole slot 10 in the lock plate 9. With the enlarged portion of the button hole slot 10 35 in register with the opening 11 in the plate 6, the rod R is free to rotate, but upon inward movement of the plate 9 to cause the adjacent portion of the rod R to be received within the restricted portion of the button hole slot 10, said rod R is effectively held 40 against rotation.

23 denotes a screen fabric of requisite dimensions, and one end portion of said screen has secured thereto a binding 24 of textile material, said binding extending beyond the adjacent margin or edge of the sheet 23, said extended portion being formed, through the instrumentality of the row of stitching 25, into a casing 26 through 45 which the rod R is directed. By fact of the binding 24 being of textile fabric and the rod R being angular in cross section, turning movement of the rod R in one direction will result in the requisite winding 50 of the screen fabric 23 upon the rod R and without slippage. In winding the screen fabric 23 upon the rod R the lock plate 9 is adjusted manually to prevent the enlarged portion of the slot 10 from registering 55 with the opening 11 to permit the desired rotation of the rod R and also to cause the restricted portion of the slot 10 to receive the rod to hold said rod R against rotation. While any means that can be employed with facility and convenience may be

employed for rotating the rod R, I prefer to employ a wrench W of the type illustrated in the accompanying drawings.

The end marginal portion of the screen fabric 23 remote from the binding 24, is secured to an angular plate 27 of a length coextensive with the width of the fabric 23. The plate 27 is preferably substantially L-shaped in cross section and when the housing or receptacle H is in applied position and the screen fabric 23 disposed across the window opening, a flange of said plate is engaged with the inwardly facing hooks 28 carried by the jamb J remote from the applied housing or receptacle H.

In applying my improved screen, or more particularly the housing or receptacle H, the upper extended portion of the rod R is disposed through the opening 11 in the plate 6 and through the enlarged portion of the slot 10 in the lock plate 9 and with the housing or receptacle H angularly disposed with respect to the jamb J, which is permitted in view of the fact that the plate 5 is supported by its associated jamb J for 50 swinging movement about a horizontally disposed axis. After this arrangement, the lower portion of the housing or receptacle H is swung downwardly, the lower end readily passing over the finger 4, owing to the 55 resiliency of said finger. This permits the housing H to be supported directly upon the sill S with the finger 4 extending slightly above the lower end of said housing or receptacle H whereby the same is effectively maintained in applied position.

In lieu of the screen fabric 23, a woven or textile fabric 23^a, as illustrated in Figure 8, may be employed, and especially when it is desired that the device be used as a 105 ventilator as in the winter time.

With a screen constructed in accordance with an embodiment of my invention it will be readily understood that the same may be applied in the working position and when the fabric 23 is not in use, the same may be readily stored within said housing or receptacle H and held or supported by the associated jamb J. Under these conditions the housing or receptacle H forms no undue 115 hindrance to the window opening.

When it is desired to employ my improved device only in connection with one of the sashes of the window, or when the screen fabric or ventilating fabric is of a width less than the full extent of opening movement of the coacting sash, I provide a supporting plate 28 which has a longitudinal marginal portion overlying a parting strip 29, while the opposite longitudinal marginal portion of the plate 28 is provided with an inwardly directed flange 30 which contacts with the adjacent jamb J'. Holding screws 31 are disposed through the plate 28 and engaged with the jamb J' 130

although it is to be understood that this plate 28 may be held in applied position in any manner which complies with the requirements of practice. One end portion 5 of the plate 28 has operatively engaged therewith a plate 5 constructed as hereinbefore referred to and having the same parts coacting therewith. The opposite end portion 10 of the applied housing or receptacle contacts with a plate 1 or more particularly a finger 4, as hereinbefore set forth.

What is claimed is:—

1. A screen structure for windows comprising a casing containing a roller having a screen wound thereon, the casing having a slot through which the screen may be drawn to be extended across the window opening, and means for mounting said casing on the window frame, said means comprising an ear at the upper end of the casing pivotally mounted upon one side of the window frame, a plate secured upon the window sill and formed with an upstanding flange arranged in spaced parallel relation to the adjacent side of the window frame, and an upwardly extending spring tongue on said plate engageable by one side

of said casing for maintaining the casing in vertical position against the side of the window frame. 30

2. In a device of the character described, an upright casing having a slot therein, a roller journaled within said casing and having a screen wrapped thereon, the casing being formed with a slot through which 35 said screen may be drawn, a bearing at the lower end of the casing for the lower end of the roller, the upper end of the roller being rectangular in cross section, a cap on the upper end of the casing having an opening through which said roller is rotatable, 40 guides on said cap, and a plate slidable within said guides and having a keyhole slot accommodating the upper end of the roller, said keyhole slot having an angular 45 portion of a size to receive the roller end and hold the roller against rotation and further having an opening of such size as to register with said first named opening to permit 50 rotation of the roller.

In testimony whereof I hereunto affix my signature.

MATTHIAS A. DIETRICK.
